UNITED STATES PATENT OFFICE.

ZENAS P. CANDEE, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

FEED MECHANISM.

1,252,396.

Specification of Letters Patent.

Patented Jan. 8, 1918.

Application filed June 1, 1916. Serial No. 101,199.

To all whom it may concern:

Be it known that I, ZENAS P. CANDEE, a citizen of the United States, residing at Waterbury, in the county of New Haven 5 and State of Connecticut, have invented certain new and useful Improvements in Feed Mechanism, of which the following is a specification, reference being had therein to the accompanying drawings.

10 My invention has particular reference to new and improved feed mechanism and especially to so much thereof as relates to the feeding of blanks or articles separately from a column or row of such blanks or articles.

15 It is the object of this invention, among other things, to provide a simple device by which blanks or articles, having a more or less intermeshing engagement with each other, may be taken singly from a column 20 of such blanks or articles and conveyed to a delivery point, such device to be composed of but few parts and these of such simple design that they may be economically constructed and readily assembled.

25 To these, and other ends, my invention consists in the feed mechanism, having certain details of construction and combinations of parts, as will be hereinafter described and more particularly pointed out 30 in the claims.

Referring to the drawings, in which like numerals of reference designate like parts in the several figures;

Figure 1 is a fragmentary side elevation 35 of my improved invention with the parts in the relative position occupied by them when the blank or article is in its first or initial position;

Fig. 2 is a sectional view of such portion 40 of said parts in their relative positions as is essential to show the second position of the said blank or article in the sequence of movements;

Fig. 3 is a similar view illustrating the 45 third position of the said blank or article; and

Fig. 4 is a sectional view of the parts, 50 with the blank or article delivered ready for an operation, that is, its fourth and last position.

My invention is especially adapted to feed blanks or articles consisting essentially of hollow cylindrical bodies having one solid projecting end which may either be

rounded or of other similar form, and for 55 the purposes of illustration such form of blanks or articles is shown in the drawings and described in this specification, but however do not desire to be limited to such form of blank or article.

60 It has heretofore been practically impossible to automatically feed such blanks or articles owing to their intermeshing relation with each other, which difficulty is increased proportionately to their length if the blanks 65 or articles are attempted to be separated singly from a column thereof and at an angle thereto, little or no difficulty being experienced if the blanks or articles are taken singly from the column in the same 70 direction as they lie therein.

The invention is shown as applied to a power press, but this is only for the purpose of illustration, as the mechanism can be applied to any other form of mechanism as 75 may be desired.

In the drawings, the numeral 1 designates the bed or base of the apparatus, 2 a die, having an opening 4 therein of the desired shape and size, mounted within a die ring 5 80 and resting against a backing block 3.

Adjustably secured to a fixed part by the screw 6 is a stop 7, the face 8 of which is shown in line with one edge of the opening 4.

Movably mounted in the bed 1 is the slide 9, having a pocket 10 in the end thereof adjacent to said die. The means requisite for reciprocating this slide are not material to this invention and are not therefore 90 herein shown.

Secured to the bed or base 1 is a bracket 11, within which the tube holder 12 is pivotally connected by the pintle 13. A spring 15 connected to a screw 16 in said tube 95 holder and to a fixed post 17 provides means for moving said tube holder in one direction, which is limited by the stop screw 14 threaded in said bracket 11 and upon which is the jam nut 18.

100 The means for conveying the blanks or articles from the hopper, or other source of supply to the tube holder 12 are herein shown as a flexible tube 19, the lower end of which projects into the tube holder a 105 sufficient distance to provide support therefor. In operation, the articles pass through this flexible tube in substantially the rela-

tive position shown in Fig. 1, the rounded end of one blank or article projecting into the open end of the article just below it.

When the slide 9 is in such position that 5 the pocket 10 therein is below the tube holder 12, one of the blanks or articles, designated herein by the numerals 20, drops from the tube holder into said pocket. The slide now begins to move toward the die, 10 and while the blank or article 20 is assuming the position shown in Fig. 2, it rocks against the rounded end of the blank or article next above it. As the slide continues its forward movement the tube holder 12 rocks 15 upon the pivot mounting 13 and permits the blank or article to become disengaged therefrom, the then position of the tube holder and the relative position of the two lower articles in the column being shown in Fig. 3. 20 The slide 9 continues its movement until the article is brought into contact with the face 8 of the stop 7, when it registers with the opening 4 in the die 2, and either drops therein by gravity or by the action of the 25 tool (not shown) that is moved into position to engage it. At the same time the spring 15 returns the tube holder 12 to its original position against the stop screw 14 and another blank or article drops into the pocket 30 10 when it registers with said holder, and the operations are repeated as before.

There are minor changes and alterations that may be made within my invention, aside from those herein suggested, and I would 35 therefore have it understood that I do not limit myself to the exact construction herein shown and described, except as defined by the appended claims.

Having described my invention, what I 40 claim as new and desire to secure by Letters Patent, is:—

1. In mechanism for feeding a blank or article at an angle from a series of blanks or articles which are partly interlocked, a reciprocating member and a holder for said series of blanks or articles, to which holder movement is imparted by said reciprocating member through the medium of the blanks or articles.
2. In a mechanism as described, a blank guiding member supported by a movably mounted member to which movement is imparted through the medium of the contents of said blank guiding member by an independently actuated member.
3. In a mechanism as described, a reciprocating member, a blank guiding member

supported by a movably mounted member which is moved from its initial position by means of said reciprocating member through 60 the medium of the contents of the blank guiding member, and means for returning said movably mounted member to its initial position.

4. In a mechanism as described, a reciprocating member, a blank guiding member supported by a movably mounted member to which movement is imparted by means of said reciprocating member through the medium of the contents of said blank guiding 70 member, and means for limiting the movement of said movably mounted member.

5. In a mechanism as described, a flexible blank guiding member capable of containing a column of blanks or articles, a movably mounted holder for said blank guiding member, a reciprocating member imparting a movement to said movably mounted holder through the medium of the contents of said blank guiding member and having a pocket 80 therein for the reception of the blanks or articles from said blank guiding member and for conveying them therefrom.

6. In a device of the character described, the combination with a reciprocating member, having a blank receiving opening therein; of a tube holder movably connected with a fixed part; and adjustable means for limiting the movement of said tube holder in one direction whereby blanks as they pass 90 through said tube holder will successively drop into said blank receiving opening when the same is in register therewith, said reciprocating member when moving in one direction imparting movement to said tube holder 95 through the medium of the blank in said blank receiving opening.

7. A blank guiding member supported by a movably mounted member, said blank guiding member being adapted to support a 100 series of axially aligned and interengaging blanks, a movable feeding device to which said blanks are successively fed from said blank guiding member, said feeding device and said movably mounted member being 105 relatively so arranged that movement of said feeding device in engagement with a blank will feed the blank and move the movably mounted member so that the blank will be disengaged from the next succeeding 110 blank.

In testimony whereof I have hereunto affixed my signature.

ZENAS P. CANDEE.
